UNITED STATES PATENT OFFICE.

ROMEDIUS PANZL, OF MUSKEGON, MICHIGAN.

APPARATUS FOR MANUFACTURE OF POSTS AND THE LIKE OF REINFORCED CONCRETE.

1,152,210.

Specification of Letters Patent. Patented Aug. 31, 1915.

Application filed February 12, 1915. Serial No. 7,736.

To all whom it may concern:

Be it known that I, ROMEDIUS PANZL, a citizen of the United States, and a resident of Muskegon, county of Muskegon, and State 5 of Michigan, have invented certain new and useful Apparatus for Manufacture of Posts and the like of Reinforced Concrete, of which apparatus the following is a full, clear, and exact specification.

10 Concrete, or artificial stone posts for fences and other purposes, possess the advantage of greater durability and resistance to rotting and corroding, as compared with wooden, or iron posts, yet their more extensive use was heretofore prevented by the fact, that without reinforcement with metallic rods, they are not safe, being liable to be broken by impact, and that the costs of manufacture of so reinforced concrete, or 15 artificial stone, posts as heretofore pursued, renders the product too expensive.

The object of my invention is to provide an apparatus, by which reinforced concrete posts may be produced rapidly and cheaply, 20 and the posts also provided with means for attaching fence wires thereto, so that the wires, or fence bars, can be secured thereto.

The apparatus for this purpose, constructed according to my invention, consists 25 substantially of a form, a base and a standard for setting up the form in position, of means for setting up and maintaining the reinforcing rods in their place in the form, and of means for compacting the material 30 filled into the form.

An apparatus embodying my invention is shown in the accompanying drawing, wherein—

Figure 1 is an elevation, partly in section, 35 view of the apparatus; Fig. 2 is a cross-sectional view on line 2—2 in Fig. 1, and a plan view of the base; Fig. 3 is a cross-sectional view on line 3—3 in Fig. 1, showing a post inclosed in the form, and a 40 wire loop as placed around the reinforcing rods, with the eye of the loop, for attaching the fence wires to the post, projecting through the slot in the form; Fig. 4 is a sectional view on line 4—4 in Fig. 1, but 45 showing the doors of the form open, and also the bracket for holding the form in position, in dotted lines. In this figure the form is shown turned approximately 90 degrees 50 from the position in Fig. 1; Fig. 5 is an elevation, partly sectional view on line 5—5

in Fig. 2, showing how the reinforcing rods are set, and held in position in the base, and in the pounder; Fig. 6 is a perspective view of one of the wire loops; Fig. 7 is a plan view, showing a modified form of joining 60 together the parts of the post form; Fig. 8 is an elevation, and Fig. 9 an enlarged plan view of a reinforced concrete fence post, having transverse perforations formed 65 therein, for passing therethrough iron rods, or piping; Fig. 10 is an elevation, partly sectional view, and Fig. 11 an enlarged plan view of a hollow fence post, the core being shown as not yet removed.

The post form 14 may be round, as shown 70 in the drawing, or polygonal, according to in what shape the posts are to be produced, and is made preferably of two parts, hinged together, as shown in Figs. 1 and 4, or fitted together as shown in Fig. 7. Its dimensions 75 and shape are determined by the dimensions and shape of the posts to be produced. Near the upper end of the form an opening is provided, and a door 16, preferably made in two parts, for closing it. One or two 80 longitudinal slots 17 are provided, according to whether only one or two rows of eyes for fastening the fence wires are wanted. The slots extend from the level of the door 85 opening downward, to a point at which the lowest loop and eye is to be set in the post, and, if two are desired, they may be in line with each other, or placed at an angle. For the manufacture of posts without eyes for 90 attaching fence wires thereto, the forms need not be provided with such a slot, or slots.

The standard 13 is made preferably integral with the base 12, and preferably so extended, that the pounder 15 may be movably suspended therefrom in line with the 95 form. For this purpose, the pounder is tied to the end of a rope 27 laid over the block 26, by which the pounder is raised and dropped. The pounder 15 is used for tamping the concrete material in the form, and 100 also to assist in maintaining the reinforcing rods 21 in their position.

A recess 18 is made in the base 12, corresponding in shape and dimensions to the 105 shape and dimensions of the form 14, so that the form may be set therein. The upper end of the form 14 is held in vertical position and in alinement with the recess 18 in the base, and with the pounder 15, by the bracket arm 23, made preferably integral with the stand- 110

ard 13, and so dimensioned that the clamp, embracing the form 14, is in alinement with the recess 18 in the base.

Transversal grooves 19 and 20 are formed 5 in the bottom of the recess 18. One of these grooves is sunk below the level of the other, and each is made sufficiently deep to accommodate the crossing bends of the reinforcing rods 21, which are set therein, as shown 10 in Fig. 5. Instead of these grooves, separate recesses for each reinforcing rod may be made in the bottom of the recess 18, as shown in Fig. 11, into which the ends of the reinforcing rods 21 may be set, if it is not 15 desired to have the rods U-shaped pairs, as shown in Fig. 2. It should also be understood, that more or less than four of the reinforcing rods may be used, if desired. For the manufacture of solid posts it is, however, 20 preferable to have the reinforcing rods bent in U-shape, as shown in the drawings.

The reinforcing rods 21 are longer than the form, and their upper ends project therefrom, as shown in Fig. 1, engaging in the 25 perforations 22 of the pounder 15, whereby they are constantly maintained in a fixed relative position to the form 14, and to each other.

The apparatus as thus far described, is 30 suitable for the manufacture of solid posts. If it is desired to make the posts hollow, a core 24, as shown in Figs. 10 and 11 may be set in, concentrically into the form, for which purpose a corresponding recess in the 35 base 12 is provided. This core 24, is also longer than the form 14, and when used, a corresponding perforation is made in the pounder 15, by means of which the core is maintained in its concentric position in the 40 form. It should also be noted, that if the U-shaped form of the reinforcing rods is to be used, the lower end of the core 24 is to be correspondingly recessed.

The manufacture of such posts by means 45 of this apparatus, is proceeded with as follows: The form 14 is set up and fixed in its position, as shown in Fig. 1. Then the reinforcing rods 21 are set in place, the pounder having been raised out of the way. 50 Then the pounder is slowly let down, while the operator holds the projecting ends of the reinforcing rods in position, so they will enter the perforations 22 in the pounder, as the latter is let down. Next the door 16 is 55 opened and swung aside, as shown in Fig. 4, and a portion of the material (concrete, or artificial stone mixture) of which the post is to be made, is dropped in into the form through the door. This material is dropped 60 in into the form successively, the pounder being used to compact each instalment of the material. When the level of the material reaches the point, at which the first loop (or perforation) is to be made, the pounder is 65 raised above the door, and a loop or tie 28,

like that shown in Fig. 6, formed preferably of stout galvanized wire, is placed in, through the door 16, around the reinforcing rods 21 and so that the eye 29, which is to project from the post, lies in the slot 17 as 70 shown in Fig. 3. If the eyes 29 are to be on two (or more) sides of the post, additional loops 28 are so placed with the eyes in opposite slots, or angularly disposed relatively to each other. The loop is then pushed down 75 by the pounder 15, and pressed into the still soft material of the post. Then the pounder 15 is again raised above the door, and the next instalment of the material is charged in into the form, and compacted by the 80 pounder, as explained.

When the level of the material has reached the point, at which the second, or next following tie, or loop 28 is to be set, the above 85 explained operation is repeated, and the work is progressively continued, until the level of the door 16 is reached. It will be noted that a notch 17^a is made in the upper edge of the lower half of the door 16, and in the lower edge of the upper half. The 90 object of this is to enable the last loop 28 to be set in, in position, through the upper half of the door 16, the lower half of the door 16 having been closed. After this has been done, the upper half of the door 16 is closed 95 and fastened, and the balance of the material, required to complete the post, is dropped in, in successive instalments through the upper opening of the form and compacted in the same way as heretofore explained. Then the pounder is raised, and the projecting ends of the rods 21 may then be cut off, and the upper end of the post suitably finished, flat or in the shape of a conus, or a pyramid, or otherwise, as may be desired. If the posts 100 are to be topped by ornamental heads, or by transverse coping, it is preferable to leave the ends of the reinforcing rods 21 projecting therefrom, and to utilize them for connecting thereto the coping, or the heads, etc. 110

If the posts are to be used for constructing a fence of iron rods, or of piping, it is preferable to provide them with perforations 31, as shown in Figs. 8 and 9. In such a construction, no eyes 29 are formed on the 115 loops or ties 28, and the perforations are made in the posts at the points where the iron rods, or piping, is to be run therethrough. This is effected by placing in the form 14, at such points, where the perforations are to be, correspondingly dimensioned cores to lie transversely through the center of the posts. These cores may also have their ends correspondingly recessed to fit into the slots 17 of the form, or perforations should be made at those points in the form for safely maintaining the cores in their proper position.

When the post is finished, as herein explained, the semi-circular latch 32 of the 130

bracket arm 23 is opened, and the form with the post within is swung out. It is best to have suitable attachments provided on the form for swinging it first into a horizontal 5 position, and then away to where the form (with the post) is to be deposited. It should be laid in approximately horizontal position, and the material in the form allowed to set, whereupon the form may be opened and 10 the finished and hardened post rolled out. There must be, of course, a sufficient number of the forms—and also of the cores—provided, as the posts should not be removed therefrom until the material has set and 15 sufficiently hardened.

I claim as my invention:

1. An apparatus for manufacturing posts, pillars and the like, of reinforced concrete, the apparatus comprising a hollow cylindrical form, an opening in the side thereof; a base; means for centering the form in position in the said base; recesses in the base for reinforcing rods to be set up within the form, a pounder fitted into the form, and 20 provided with perforations, adapted to receive the upper ends of the reinforcing rods, and to maintain the same in position in the form; a standard; a block, and a rope, for movably suspending the pounder above, and 25 substantially as herein shown and described.

2. An apparatus for manufacturing posts, pillars and the like, of reinforced concrete, the apparatus comprising a hollow cylindrical form, provided with a side aperture, and with a slot extending longitudinally therefrom, means for closing the aperture; a base; 30 means for centering the form in position in the said base; recesses in the base for reinforcing rods to be set up within the form, a pounder fitted into the form, and provided 35 with perforations, adapted to receive the upper ends of the reinforcing rods, and to

maintain the same in position in the form; a standard; a block, and a rope, for movably suspending the pounder above, and in alinement with, the form, and for operating it to compact the material charged into the form, 50 substantially as herein shown and described.

3. An apparatus for manufacturing posts, pillars and the like, of reinforcing concrete, the apparatus comprising a form composed of two hollow semi-cylindrical parts fitted 55 together, an aperture in the side of the form near one end thereof, a cover, fitted upon the aperture and means for securing it thereon, a slot in the form extending from the aperture to near the other end of the form; a 60 base, a recess in the base for centering the form in upright position, a pounder fitted into the form and means connected therewith for operating the pounder to tamp the material charged into the form; substantially as herein shown and described.

4. An apparatus for manufacturing posts, pillars and the like, of reinforced concrete, the apparatus comprising a form composed of two hollow semi-cylindrical parts fitted 70 together, an aperture in the side of the form near one end thereof, a cover fitted upon the aperture and means for securing it thereon, a slot in the form extending from the aperture to near the other end of the form; a 75 base, recesses in the base for centering therein the form, and the reinforcing rods set up within the form; a pounder fitted into the form, and provided with perforations, arranged and adapted to receive the reinforcing rods, a standard; a block, and a rope, for movably suspending the pounder above, and in alinement with, the form, and for operating it to compact the material charged 80 into the form, substantially as herein shown 85 and described.

ROMEDIUS PANZL.
